Application March 7, 1956, Serial No. 570,178

Claims priority, application Germany April 6, 1955

8 Claims. (Cl. 118—247)

This invention relates generally to a conveying and glue coating apparatus for paper strips or the like used in wrapping the tips of filter cigarettes.

In the manufacture of filter tip cigarettes one method provides transporting of the incompletely cigarettes on a drum having circumferentially spaced grooves in its surface. These grooves substantially parallel the rotational axis of the drum and are of sufficient length to accommodate two full length cigarettes in end to end relation therein. As is well known, a filter-tip cigarette comprises a tobacco filled paper wrapped body with a cylindrical filter abutting the end of the cigarette body. The filter and the cigarette body are joined by a thin paper band, or any other suitable type of band, such as a thin cork wrapping, which encircles the filter and overlaps the cigarette body to form an integral assembly.

With apparatus of the type referred to the filter-tips are double the required length for a single cigarette and are disposed between the cigarette bodies in the grooves of the drum. The paper band which is wrapped about the filter tip is also of twice the required width to span the double-length filter-tip and overlap the cigarette bodies. Thus a double length cigarette is formed in the process and by cutting the double length cigarette in its middle, through the center of the double length filter, two completed cigarettes are formed.

The cigarette tip wrappers are obtained from a roll of thin tip wrapping material which is automatically drawn through a gluing and cutting arrangement synchronized with the cigarette carrying drum. The paper strip, which is of twice the width required for a single wrapper to span the double length filter-tip and overlap the cigarette bodies as described, is drawn over a conventional glue coating roller and thence passes over a cutting roller drum with its glue-coated face up where it is cut into suitable lengths to wrap completely about the filter-tip and cigarette body. The cigarettes on the cigarette carrying drum pass adjacent the cutting roller and respectively engage the adjacent individual tip wrappers which due to the moist glue adhere thereto and are carried with the cigarettes to the tip wrapping mechanism.

Such prior art arrangements operate satisfactorily as long as operation is continuous. However, if the operation is interrupted for any reason, the glue coating dries on cut and uncut portions of the strip between the glue coating stage and the tip wrapping stage. When the glue dries, the paper curls which tends to foul the apparatus. Also the strip tends to stick to the coating roller which may break the paper web at that point when the operation is started up again.

Accordingly, it is an object of this invention to provide a conveying and glue coating arrangement for thin strip materials in which fouling of the apparatus due to drying of the glue on coated portions is prevented when the coating operation is stopped.

More specifically it is an object hereof to provide a conveying and glue coating arrangement for thin strip materials wherein provision is made for interrupting the coating operation when the apparatus is stopped.

2

The foregoing statements are merely illustrative of the various aims and objects of this invention. Other objects and advantages will become apparent from a study of the following specification when considered in conjunction with the accompanying drawing, in which the single figure illustrates a conveying and glue coating apparatus, for thin strip materials, embodying the principles of this invention.

The apparatus illustrated comprises generally a conveying, glue coating and cutting machine generally designated 1 which processes the filter tip strip material 2 and transports the coated and cut tip wrappers 3 formed therefrom to a position where they are sequentially engaged and picked up by respective cigarette assemblies 4, carried in grooves in a cigarette transporting drum synchronized with the production of the coated tip wrappers 3.

In the device 1 the strip 2 passes over a guide roller 6 and then threads between a pressure roller 7 and a driving roller 8. The paper roll from which strip 2 is drawn is not shown. The strip 2 then passes over a spool shaped roller 9 and beneath an idler roll 10, threading between a pair of guide rollers 11 and 12 which are mounted on the end of a lever 13 pivotally mounted about a fixed pivot 14 secured in the support plate 15. Upon leaving the guide rollers 11 and 12, the strip passes over a glue coating roller 17 rolling against a roller 18 partially immersed in the liquid glue in a glue container 26. From the glue coating roller 17 the strip proceeds about a cutting roll 22 driven by suitable means (not shown) in synchronism with the strip speed established by drive roller 8, where it is engaged by a synchronized rotary cutter 23 which forms the individual coated wrappers 3. The coated strip engages the cutter roll 22 with its glue coated face up and may be temporarily held thereagainst by suction pressure within the drum in keeping with conventional practice. As the cut wrappers move from cutting position with rotation of the cutter roller, they are engaged by the cigarette assemblies 4 and adhere thereto to be transported therewith to the wrapping stage (not shown).

Lever 13 is shown in operating position, which is the position in which the strip 2 is held against coating roller 17 to be glue-coated when the machine is running. However when the machine is stopped, provision is made to move lever 13 to the position indicated in dotted outline, which displaces guide rolls 11 and 12 sufficiently to lift strip 2 from coating roller 17 to interrupt the glue coating operation. Such lifting of the strip is preferably accomplished prior to the time the machine stops completely, so that all coated portions may be processed into completed tips before the glue coating dries.

Movement of lever 13 is controlled by a suitable lever arm extension 25 which in turn is controlled by a suitable latch mechanism which is selectively manually or electro-magnetically operated. Lever 13 is spring loaded to operative position by means of a tension spring 26, in which position latch arm 27 of a bell crank 28, pivotally mounted at 28a, engages a catch 29 at the end of lever arm extension 25 to lock the lever arm in operative position. Trip arm 31 of bell crank 28 is engaged by a trip rod 32 secured to a slotted fork 33 on the end of plunger rod 34 of an electromagnetic solenoid 35, the coil of which is adapted for energization at terminals A and B. The plunger is shown in its fully extended position and the trip arm of the bell crank is biased against the end of trip rod 32 by a tension spring 27a which maintains a clockwise restoring or setting bias on the bell crank latch about its pivot 28a. Fork 33 on the end of plunger rod 34 is slotted at 36 to slidably receive a pin 37 secured 70 in lever arm extension 25. The lost motion provided in

the slot is sufficient to allow the latch arm 27 of the bell crank 28 to trip free of catch 29 when the bell crank is actuated by the trip rod 32. Thereafter the upper end of slot 36 engages pin 37 rotating lever assembly 13 to its dotted position to lift the strip 2 from the glue coating roller 17.

This tripping and actuating operation may be accomplished either manually or electrically as required. For example, if it is desired to stop the machine, the solenoid 35 may be energized through suitable electrical interlocking switching of conventional character with the stop switch mechanism of the machine (not shown). Thus depending upon the nature of the control desired or required, the lever 13 may be moved to inoperative position just prior to or exactly with stopping of the machine. If the first of the two suggested operating modes is selected, lever 13 may be moved to inoperative position a short time interval prior to stopping so that the glue coated strip may be cut and wrapped prior to complete stopping. If the second operating mode is desired, the interlocking may provide simultaneous energization of the solenoid when the stop switch is operated to stop the machine.

For manual operation the trip rod 32 is equipped with a handle 38 at its outer end arranged to provide a surface against which hand pressure may be applied to thrust the trip rod 32 downwardly. Manual operation of the trip rod accomplishes the same tripping sequence as the solenoid operation, first rotating bell crank 28 counterclockwise to release latch arm 27 from catch 28 and thereafter engaging the upper end of slot 36 with the pin 37 to move lever 13 clockwise to its inoperative position, which lifts the strip 2 from coating roller 17. Thus the manual feature permits lifting of the strip 2 from coating roll 17 during operation of the machine.

Provision is also made for holding lever 13 in its inoperative position. This is accomplished by means of a spring loaded plunger pin 41 which is spring loaded to released position in lever 13. When lever 13 is in inoperative position, the plunger pin 41 is indexed with a hole 42 in back plate 15. The plunger is then pushed through or into hole 42 against the spring loading and when the lever 13 attempts to return the plunger is prevented from springing back, since it is frictionally engaged with the side of hole 42. The plunger 41 may be tripped to release lever 13 at any time it is desired by applying slight manual pressure to trip rod 32 which works against the spring loading of lever 13 sufficiently to release the frictional restraint on the plunger pin 41. The plunger spring now biases the plunger to released position freeing lever 13.

If the machine is stopped when the lever 13 is latched in inoperative position by plunger pin 41, the upper end of slot 36 in the plunger 42 engages pin 37 and moves the lever 13 slightly counterclockwise before the solenoid plunger stroke is completed. This also releases the plunger pin 41 so that when the machine is started, the lever will automatically return to its operative position.

This description indicates the solenoid is to be energized with stopping of the machine. Usually a solenoid such as 35 is rated for intermittent duty in keeping with its intermittent duty cycle. Under such circumstances prolonged energization, as when the machine is shut down for a protracted period for adjustment, may damage the solenoid. Thus a suitable time delay switch time delayed on drop out may be included in the solenoid circuit to open the circuit a short predetermined time interval after energization.

Although but one embodiment of this invention has been illustrated and described, it will be appreciated by those skilled in the art that numerous modifications of this invention may be made, both in its details and in the organization of such details without departing from the spirit and scope of this invention. Accordingly, it is intended that this disclosure shall be construed only as

illustrative of the principles of this invention and not interpreted in a limiting sense.

The invention is claimed as follows:

1. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a spring engaged with said lever and biasing said lever to said operative position to engage said strip with said glue coating means, electro-magnetic means for moving said lever to said inoperative position and to move said strip out of engagement with said glue coating means, and manual actuating means associated with said electro-magnetic means adapted to be optionally actuated for moving said lever to said inoperative position to disengage said strip from said glue coating means independently of said electro-magnetic means.

2. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a spring engaged with said lever and biasing said lever to said operative position to engage said strip with said glue coating means, and electromagnetic means connected with said lever and arranged to move said lever to inoperative position to disengage said strip from said glue coating means upon energization of said electromagnetic means.

3. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a spring engaged with said lever and biasing said lever to said operative position to engage said strip with said glue coating means, electro-magnetic actuating means for rocking said lever to its inoperative position disengaging said strip from said glue coating means, and a manually operated linkage connected with said lever adapted to be optionally operated to move said lever to said inoperative position disengaging said strip from said glue coating means independently of said electro-magnetic actuating means.

4. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a latch spring loaded to engage said lever in operative position and prevent movement of said lever to inoperative position, a lost motion linkage connected with said lever and having a part engaging said latch, and electro-magnetic means operating said lost motion linkage to move

said part to trip said latch and disengage said lever whereupon said lost motion linkage moves said lever to inoperative position and optional actuating means adapted to be controlled manually independently of said electro-magnetic operating means to operate said lost motion linkage and disengage said strip from said glue coating means.

5. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a latch spring loaded to engage said lever in operative position and prevent movement of said lever to operative position, a lost motion linkage connected with said lever and having a part engaging said latch, and electro-magnetic means engaging said lost motion linkage and operable when energized to move said lost motion linkage and said part causing said part to move said latch to disengage said lever whereafter said lost motion linkage moves said lever to said inoperative position.

6. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a spring engaged with said lever and biasing said lever to said operative position to engage said strip with said glue coating means, electro-magnetic and manual actuating means adapted to be optionally actuated for moving said lever to said inoperative position to disengage said strip from said glue coating means, and a spring returned locking device adapted to be moved to a locked position when said lever is in said inoperative position and secured frictionally in locked position due to friction force thereon resulting from said spring bias on said lever biasing said lever toward operative position, said locking device being released by operation of said actuating means to reduce the friction locking force whereafter said spring returned locking device is released.

7. A conveying and gluing apparatus for the manufacture of glue coated wrappers for filter tip cigarettes wherein the wrappers are cut from a glue coated strip which

passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a spring engaged with said lever and biasing said lever to said operative position to engage said strip with said glue coating means, electro-magnetic means connected with said lever and arranged to move said lever to inoperative position to disengage said strip from said glue coating means upon energization of said electromagnetic means, and a spring returned locking device manually actuated to locked position when said lever is in said inoperative position and secured frictionally in locked position due to friction force thereon resulting from the bias of said lever biasing spring on said lever, said locking device being released when said electro-magnetic means is energized to further move said lever into inoperative position to reduce the frictional holding force on said locking device releasing said spring loaded locking device.

8. A conveying and gluing apparatus for the manufacture of glue coated wrappers for filter tip cigarettes wherein the wrappers are cut from a glue coated strip which passes over a suction pressure roller with the glue coated face up which comprises, a glue coating means disposed to engage said moving strip, movable guide rollers between which said strip passes, a pivotally mounted lever mounting said guide rollers for movement between operative and inoperative positions engaging and disengaging said strip with said glue coating means, a spring engaged with said lever and biasing said lever to said operative position to engage said strip with said glue coating means, a manually operated linkage connected with said lever and arranged to move said lever to said inoperative position disengaging said strip from said glue coating means, and a spring returned locking device manually actuated to locked position when said lever is in said inoperative position and secured frictionally in locked position due to friction force thereon resulting from the bias of said lever biasing spring on said lever, said locking device being released by operation of said manually operated linkage to move said lever further into inoperative position which reduces the friction force on said spring loaded locking device permitting said locking device to be released.
